UNITED STATES PATENT OFFICE

2,539,861

WRENCH WITH WORK ENGAGING
STEADYING MEANS

George C. Robinson, Los Angeles, Calif.

Application December 3, 1946, Serial No. 713,620

1 Claim. (Cl. 81—57)

1

This invention relates to new and useful improvements and structural refinements in wrenches, and the principal object of the invention is to provide a device of the character herein described wherein the work engaging head will be actuated with considerably greater amount of power by the expenditure of relatively lesser effort on the part of the operator, as compared with wrenches of conventional design.

A further object of the invention is to provide a wrench which is simple in construction, dependable in operation, and which may be effectively employed in restricted or poorly accessible locations.

Another object of the invention is to provide a wrench which will readily lend itself to economical manufacture and which may be easily disassembled for purposes of inspection or repair.

With the above more important objects in view, and such other objects as may become apparent as this specification proceeds, the invention consists essentially of the arrangement and construction of parts as illustrated in the accompanying drawings, in which:

Figure 1 is a plan view of the invention.

Figure 2 is a cross sectional view, taken substantially in the plane of the line 2—2 in Figure 1, and

Figure 3 is a cross sectional view, taken substantially in the plane of the line 3—3 in Figure 2.

Like characters of reference are used to designate like parts in the specification and throughout the several views.

Referring now to the accompanying drawings in detail, the invention consists of a wrench designated generally by the reference character 10, the same embodying in its construction a pair of spaced parallel side plates 11, configurated substantially as shown and connected together by a marginal enclosure 12 so as to provide what may be referred to as the housing 13.

The plates 11 are formed with a pair of transversely aligned, circular openings 14 adapted to receive a rotatable head 15, this being provided with a suitable, preferably hexagonal recess 16 which constitutes a socket for receiving the work, such as a nut or a head of a bolt.

The head 15 is provided at the periphery thereof with a plurality of gear teeth 17, these meshing with an intermediate gear or pinion 18 which is rotatable on a transversely extending pin 19 secured in the side plates 11.

A further transversely extending pin 20 is provided in the housing 13 and a ratchet gear 21,

2

meshing with the pinion 18, is rotatably mounted on this pin, as will be clearly apparent from the accompanying drawings.

A tubular handle 22 is formed at one end thereof with a pair of spaced ears 23 which are pivotally, that is, rotatably mounted on the pin 20 and straddle the ratchet 21, as is best shown in Figure 2. It will be noted that the continuity of the marginal enclosure 12 is interrupted to provide an opening 24, whereby the attachment of the handle 22 to the housing 13 is facilitated.

The handle 22 is equipped adjacent the pivoted end thereof with a transversely extending pin 25, this carrying a rotatable pawl 26. The pawl is equipped with a pair of spaced dogs 27 which are selectively engageable with the ratchet 21, and a further pair of spaced dogs or lugs 28 are provided on the pawl, as is best shown in Figure 3.

One end of the flat spring 29 is positioned between the lugs 28, while the remaining end portion of the spring is anchored in a suitable slot formed in a pin 30 secured in the handle 22. The latter is also formed with a transversely disposed slot 33 which receives a slidably, button-like member 34. The intermediate portion or shank of this member is slotted to receive the spring 29, as is best shown in Figure 3.

It will be noted that the housing 13 is provided with a laterally projecting extension 35 which terminates in a pressure pad 36 hereinafter to be more particularly referred to.

Finally, it will be observed that the side plates 11 of the housing are separably attached to the enclosure 12 by a plurality of suitable screws 37 to facilitate convenient disassembly of the housing for purposes of inspection and repair.

The free extremity of the handle 22 is formed with a pair of transversely aligned apertures 38 whereby the wrench, when not in use, may be conveniently suspended from a suitable nail or hook on a wall.

When the invention is placed in use, the socket 16 is simply applied to the work, such as a nut or the head of a bolt, whereupon the button 34 is slid to one or the other end of the slot 33. This action will result in the engagement of one or the other of the dogs 27 with the ratchet 21 as is facilitated by a provision of the spring 29.

Thereupon, the handle 22 may be oscillated in the direction of the arrows 39 and the movement of the handle in one direction will be transmitted through the medium of the pawl 26 to the ratchet 21 and hence through the medium of the pinion 18 to the head 15. Accordingly, an interrupted, unidirectional motion will be imparted to the head

and to the work engaged thereby. However, since the gears 18 and 21 are of relatively smaller diameter with respect to the head 15, considerable mechanical advantage will exist and the head will be rotated with relatively greater power or torque, as compared to the exertion of small effort on the part of the operator.

The head 15 may be rotated in an opposite direction by simply sliding the button 34 to the opposite end of the slot 33, thereby engaging the remaining of the dogs 27 with the ratchet 21, as will be clearly understood.

It should be understood that while the handle 22 is being manipulated, the housing 13, as a whole, should be held stationary by the operator, this being a relatively easy task when the work is in the initial stages of tightening or in the advance stages of loosening.

To provide against the tendency of the housing to rotate in the anticlockwise direction when the wrench is operated under full load as in the final stage of tightening, the pad 36 may be brought in contact with suitable structure adjacent the work, or it may be held stationary by some other suitably devised means, and rotation of the housing will thus be prevented.

It is believed that the advantages and use of the invention will be clearly understood from the foregoing disclosure and accordingly, further description thereof at this point is considered unnecessary.

While in the foregoing there has been shown and described the preferred embodiment of this

invention it is to be understood that minor changes in the details of construction, combination and arrangement of parts may be resorted to without departing from the spirit and scope of the invention as claimed.

What I claim as my invention is:

In a heavy duty wrench, the combination of a housing containing an externally toothed and rotatably mounted work-engaging socket, an oscillatory actuating handle pivoted to said housing, a train of reduction gears operatively connecting said handle to said socket, and an outwardly extending rigid stabilizing finger provided integrally on said housing, said finger terminating in a work engaging pressure pad.

GEORGE C. ROBINSON.
